UNITED STATES PATENT OFFICE

2,572,704

BOTTLE-CAPPING MACHINE

Arthur H. Edgerton, Rocky River, Ohio, assignor
to Harold D. Laidley, Cleveland, Ohio

Application April 30, 1947, Serial No. 744,926

8 Claims. (Cl. 226—83)

1

This invention relates broadly to bottle capping machines and more specifically to mechanism for the fabrication and affixation of waterproof caps to the top and neck of bottles.

One of the objects of the invention is to apply an adhesive to one face of a continuous strip of waterproof paper or film, then progressively fabricate a blank therefrom, draw the blank over the end of a bottle, press the blank into sealed relation with the neck thereof, and as a final step in the operative cycle, draw a requisite length of new film under a punch while simultaneously advancing another bottle into position under a die.

Another object of the invention is to provide a sanitary seal for a bottle which is designed to cover the cork or crown thereon and a substantial portion of the neck.

Another object of the invention is to provide a bottle cap which is water and germ proof yet susceptible of ready removal.

Another object of the invention is to provide a sealing mechanism which is designed for automatic actuation within the operative cycle of the machine.

Another object of the invention is to provide an escapement movement which will accommodate translation of the cap film while the punch and the accessorial parts thereto are at rest.

Still another object of the invention resides in the provision of a machine which is economical in operation, capable of high speed production, sturdy and durable of structure and designed for use with minimum care and attention.

Other objects and advantages, more or less ancillary to the foregoing and the manner in which all the various objects are realized will appear in the following description and accompanying drawings wherein there is assembled and pointed out certain details of structure and aggroupment of parts connotative of the scope of the invention as defined in the appended claims.

Referring to the drawings which illustrate the preferred embodiment of the invention:

Fig. 1 is a side elevational view of the improved capping machine;

Fig. 2 is an end elevation thereof;

Fig. 3 is a plan view of the machine;

Fig. 4 is an opposite side view of a fragmentary portion of the machine illustrated in Fig. 1;

Fig. 5 is a vertical sectional view shown on an enlarged scale of the punch and sealing mechanism associated therewith;

Fig. 6 is a similar sectional view shown in an actuated position;

Fig. 7 is a sectional view through the punch illustrating the position of the sealing fingers when sprung into engagement with the neck of the bottle;

2

Fig. 8 is a transverse section through the sealing fingers, the section being taken on a plane indicated by the line 8—8 in Fig. 6;

Fig. 9 is a similar section taken on the line 9—9 in Fig. 7;

Fig. 10 is a longitudinal section through the film feed roll;

Fig. 11 is a transverse sectional view through the feed roll, the section being taken on a plane indicated by the line 11—11 in Fig. 10;

Fig. 12 is a section taken on the line 12—12 of Fig. 3;

Fig. 13 is a section taken on the line 13—13 of Fig. 3;

Fig. 14 is a vertical section taken on the line 14—14 of Fig. 3;

Fig. 15 is a transverse section through the crimping cone, the section being taken on a plane indicated by the line 15—15 in Fig. 7;

Fig. 16 is an elevational view of a gum roll of alternate form;

Fig. 17 is an end elevational view thereof; and

Fig. 18 is an end elevational view of a modified form of the punch.

25 Referring first to Fig. 1, the machine comprises generally a bed plate 10 having a cylindrical punch guide 11 mounted thereon, a gum box adjacent thereto, a paper roll stanchion 12, a feed roll 13 and a frame 14 for the support of the gears and driving connections for the punch and feed roll.

The power input is preferably taken from a gear or the pulley 15 (Figs. 4 and 14) mounted on a shaft 16 supported in a bracket 17 and a journal bearing 18 in the frame 14. The shaft 16 is provided with a pair of milled gears 19 and 20 which are keyed thereto and intermeshed with pinions 21 and 22 respectively. The pinion 21 is keyed to a shaft 23 journaled in a bearing 24 in the frame 14, the gear 22 is, however, mounted for free rotation thereon. The outer end of the shaft 23 has a crank arm 25 keyed thereto which supports a connecting rod 26 coupled with the stem of a tubular punch 27.

45 The second pinion 22 is entrained with a gear 28 (Fig. 4) having a pintle 29 thereon for the reception of a connecting rod 30 which is coupled with a push rod 31 interlinked with an arm 32 on the feed roll shaft 33. The shaft is mounted in a bored boss 34 in the frame 14 and a bearing block 35 on the bed plate 10. The central portion of the shaft is diametrically enlarged and provided with a ratchet clutch 36 (Fig. 10) which drives a sleeve 37 having pins 38 in the face thereof for piercing the paper or film under the punch in order to effect the translation thereof. The pintle 29 is positioned on the gear 28 to effect the movement of the arm 32 through an arc of ninety degrees and the arm is formed with 55 a slot 40 therein to compensate for the arcuate

movement thereof. The circumference of the sleeve is four times the dimension "a" indicated in Fig. 3, i. e. the diameter of the punch plus the web W which is of sufficient area to hold the fabricated waste material intact during the stock feed operation. Thus as the arm 32 is actuated in its operative cycle, the sleeve 37 will be revolved and the pins 38 will effect the withdrawal of the scrap from beneath the punch and the delivery of new material thereto.

The mutilated gear 19 is twice the diameter of the pinion 21 entrained therewith and the teeth on one half of the circumferential face thereof are removed, hence as the gear is revolved one hundred and eighty degrees the pinion will make one revolution and the punch 27 will be actuated throughout a complete reciprocative cycle. The crank arm 25 is positioned to reach top dead center as the last tooth on the gear 19 leaves the pinion 21. Thus as the gear 19 is rotated through the remaining portion of its cycle the plunger will be at rest in its retracted position. The pinion 21 may be held from creeping during the period in which the relieved portion of the gear 19 is rotated by any of the well known expedients, for example, the sliding engagement of a concave tooth section on the pinion with the arcuate or stripped tooth area on the gear.

The mutilated gear 20 and pinion 22 therefor are of similar construction, save that the teeth are removed from the opposite side of the gear so that the pinion 22 will be rotated when the pinion 21 is idle. It will be readily recognized from the foregoing that the stock feed roll 13 will be at rest during the reciprocative movement of the punch, and that the downward movement of the push rod 31 will effect the operation of the feed roll 13 when the punch is held in its retracted position.

The paper or film is preferably supplied in rolls 41, the width thereof being greater than the diameter of the punch 27 in order to provide adequate strength to the scrap or fabricated portion of the ribbon to facilitate the translation thereof through the machine under the tensile action of the feed roll 13. The pins 38 are disposed in the sleeve 37 of the feed roll assembly adjacent the outer edges thereof and pass through slots 41 in the die plate 42 as the sleeve is revolved thereover. The scrap may be deflected upwardly and removed from the machine in any convenient manner after it leaves the feed roll 13. As the film stock or ribbon 43 is drawn from the coil 41 it passes over a platen 44 constituting a backing plate for a gum roll 45 which is mounted in a reservoir 46 containing an adhesive such as fluidic latex or a similar waterproof gum. The roll is charged by a roller 47 mounted in the reservoir with the lower portion thereof immersed in the adhesive. The roller 47 and gum roll 45 may be provided with adjustable bearing blocks (not shown) of any conventional well known form to facilitate control of the quantity of adhesive applied to the film by the applicator roll 45. As the ribbon 43 is advanced it is supported in spaced relation with the die plate 42 by an arcuate guide 48 which terminates in the throat of a recess 49 in the base of the punch guide 11. The gummed surface of the ribbon 43 is held out of contact with the face of the die plate during the movement of the film by a roller 50 disposed adjacent the discharge end of the recess 49.

The end of the feed roll shaft 33 is provided

with a sprocket 51 (Figs. 2 and 3) having a chain thereon which is connected with a second sprocket 52 on a shaft 53 that supports a conveyor gear set and belt 54. The belt is provided with cups 55 disposed at intervals equal to the distance indicated by the dimension "a" and the gearing between the feed roll and conveyor is designed to effect equal simultaneous movement of the ribbon 43 and conveyor belt, so that the bottles mounted in the cups 55 will be moved into position under the punch upon each operating cycle of the feed roll 13.

Referring now to Figs. 5, 6 and 7, the punch guide 11 is formed with diametrically opposed slots 56 in the side wall thereof having pins 57 therein, which are provided to delimit the descent of the punch beyond a predetermined point. The punch is preferably, though not necessarily of cylindrical form and provided with an internally beveled cutting edge 58. The lower end of the punch is provided with an inwardly flared ring 59 formed with crimping grooves 60 in the tapered face thereof and a ledge in its upper face-adjacent the throat thereof. The throat or opening in the ring is slightly larger than the portion of the neck of the bottle for which the punch is designed (see Fig. 6), so that reentrant engagement of the punch may be made without the hazard of cleavage between the bottle and the ring. The upper end of the punch is provided with a cap 61 bored to facilitate free movement of the punch therein and is cross-drilled for the reception of the pins 57. The punch stem 62 is secured in a boss 63 of a plate 64 normally urged into intimate engagement with the lower face of the cap 61 by a spring 65 disposed intermediate the plate 64 and the ring 59. The spring 65 is designed to outweigh the pressure required to pierce the film or ribbon that overlies the die opening 66 but to yield under the pressure exerted through the gearing and crank arm 25 when the punch is brought to rest by engagement of the pins 57 with the bottom of the slots 56. The lower face of the plate 64 is formed with an annular boss 67 which is machined for the retention of a cap sealing element 68.

The lower face of the boss is further machined with a recess formed in configuration of the upper portion of the crown on a bottle. The sealing element 68 comprises a spring steel cylinder having kerfs 69 in the side wall thereof constituting fingers 70 and the central portion of the cylinder is bowed inwardly to provide a normal camber in the fingers 70. The smallest internal diameter of the cylindrical element 68 is slightly greater than the maximum diameter of the bottle crown or the bead adjacent the end of the bottle so that telescopic engagement of the punched and crimped blank of film within the cylinder may be made without undue frictional contact with the bottle. The lower end of the slots 56 are disposed so that the pins 57 will be engaged therewith before the crank arm 25 reaches bottom dead center, hence when the punch comes to rest and the push rod 62 and plate 64 continue their descent the cambered fingers 70 will buckle (Fig. 7) and press the gummed blank punched from the ribbon into sealed engagement with the contiguous portion of the neck of the bottle. As the punch is retracted, the fingers 70 will regain their unstressed form and permit the ready withdrawal of the sealing element. It will be noted that the squeezing action of the fingers will cause the freshly

applied gum on the uneven surface of the cupped blank of paper or film to flow in and about the crimped areas therein and thus form a homogeneous mass of adhesive which when dry will effect a tight waterproof seal.

If desired the gum may be applied by a roller which is designed to gum the central portion of the blank but leave the marginal edges thereof free from adhesive. Such a roll is illustrated in the modified form illustrated in Figs. 16 and 17, wherein the major portion of the roll is relieved but a pad or medallion 71 is provided to effect the application of the adhesive in the center of the punched blank with a narrow ungummed border about the circumference thereof. Alternately the pattern could be reversed and the roll could be formed to apply a band or strip of gum upon or adjacent the marginal edge of the blank with the central portion thereof clear. In this embodiment the gum roll would be intergeared with the feed roll so the medallion would be placed on the film with the center thereof in aligned relation with the axis of the punch as the ribbon is drawn thereunder.

The paper or film may also be pregummed, that is formed with a full or partial coating of adhesive on one side thereof. In this case the gum reservoir and applicator could be eliminated through a power driven reel and compensating gear would be required to relieve the tensile strain imposed upon the ribbon during the operative cycle of the feed roll.

A punch of an alternative form is illustrated in Fig. 18. In this embodiment the periphery of the punch and die are scalloped in order to provide finger tabs for the removal of the cap. A gum applicator which is designed to leave one or more of the tabs 72 free from adhesive is further contemplated for use in combination therewith. With a cap thus formed the tabs may be firmly gripped between the thumb and forefinger and the cap readily stripped from the bottle.

Although the foregoing description is necessarily of a detailed character, in order to define the structure, function and advantages of the invention it is to be understood that the specific terminology is not intended to be restrictive or confining and that various rearrangements of parts and alternate combinations of elements may be resorted to without departing from the scope or spirit of the invention as herein claimed.

I claim:

1. A bottle capping machine comprising a reciprocative punch, mechanism for drawing a predetermined length of film thereunder when the punch is elevated, a cone within the punch for cupping the film disc struck by the punch over the end of a bottle, yieldable fingers supported at each end within the punch, and means for deflecting the central portions of the fingers against the neck of a bottle when the punch is in its lowered position.

2. A machine for making bottle caps from a ribbon of thin waterproof fibrous material comprising a stand for the support of the ribbon, a roller for the application of a waterproof adhesive upon said ribbon, a platen for said ribbon adjacent said applicator roll, a punch for striking cap blanks from the ribbon, a plurality of resilient fingers in said punch, means for bowing the central portions thereof inwardly to press the cap blank into intimate engagement with the neck of a bottle, gearing for the intermittent reciprocation of said punch, a film feed roll and

gearing therefor operable during inactive periods of the punch gearing.

3. A bottle capping machine comprising a punch, a crank for the reciprocation thereof, gearing for the operation of said crank, a stock feed roll, intermittent gearing for the rotation thereof intergeared with said punch gearing and operable when the punch is at rest, fingers in said punch deformable toward the medial axis thereof, a stop on said punch, and a yieldable connection between said crank and said punch for bowing the central portions of the fingers inwardly when the punch is held by said stop and the crank overrides the yieldable connection.

4. A machine for forming and applying bottle caps comprising a gum applicator, a pad thereon for printing spaced areas of the gum on a film, a hollow punch for cutting blanks from the film, a cone in said punch having grooves therein for crimping the blank of film, cambered springs supported at each end within said punch, means for increasing the camber, thereby squeezing a blank upon the neck of a bottle and a feed roll operable upon the film scrap for drawing unfabricated film under the punch.

5. A bottle capping machine comprising a hollow punch for striking blanks successively from a continuous strip of film, mechanism for reciprocating said punch, a feed roll, pins on said roll for piercing the lineal edge portions of the scrap film and pulling the strip away from the punch, mechanism for rotating said feed roll before the punch engages the film, cambered spring fingers in said punch surrounding the neck of a bottle, and mechanism for increasing the camber in said spring fingers and pressing the blank punched from the strip of film into intimate engagement with the neck of the bottle.

6. A machine for capping bottles comprising mechanism for feeding a strip of paper over a platen, a roll for the application of an adhesive in spaced circular medallions along the medial axis of the strip, a punch for cutting circular blanks of a greater diameter than the medallions and concentric therewith from the strip, gearing for reciprocating said punch, spring steel inwardly cambered fingers within the punch, and mechanism for increasing the camber of the fingers and pressing the blank cut by the punch against the neck of a bottle.

7. A machine for making bottle caps from a strip of paper and assembling said caps on the top and neck of a bottle comprising a feed roll for drawing the strip of paper over a die plate, a hollow punch intergeared with said roll for cutting circular blanks from the paper strip, a gum roll disposed forwardly of the punch for the application of an adhesive upon the under side of the strip, inwardly curved spring steel fingers within the punch, a helical spring in the punch supporting the spring fingers in their unstressed form, stops on said punch to delimit the descent thereof, and a push rod coupled with said punch and engaged with said helical spring for bowing the spring fingers after the descent of the punch is arrested by said stops.

8. A machine for making and applying gummed caps on a bottle comprising a tubular punch mechanism for drawing a strip of gummed paper under the punch, a shoulder in the free end of the punch, a plate within the punch adjacent the upper end thereof, a reciprocative push rod connected with said plate, a helical spring intermediate said shoulder in the punch and said plate for pushing said punch downwardly, a plu-

rality of inwardly bowed steel fingers intermediate said shoulder and said plate, and means on said punch to delimit the descent thereof and thereby effect a greater inward deflection of the spring fingers as the push rod continues its descent, whereby a cap blank cut by the punch will be pressed into intimate engagement with the top and neck of a bottle telescopically engaged with the punch.
